SHOTSHELL

Hugh Dunn, Orange, Conn., assignor to Olin Mathieson Chemical Corporation, New Haven, Conn., a corporation of Virginia

Application August 6, 1956, Serial No. 602,285

3 Claims. (Cl. 102—42)

This invention relates to shotshells and in particularly to shotshells of the type which utilize a top shot wad.

In loading a metallic shotshell it is frequently desirable to use an envelope of resilient material such as plastic or cloth impregnated with plastic for separating the shot column from the interior of the metallic shell (see co-pending application S. N. 610,321 filed September 17, 1956 by Miller et al.). One method of conveniently arranging the envelope is to insert a collar or hollow cylinder of plastic material immediately next to the interior wall of the shotshell. The shot charge is then loaded into the shell up to a predetermined height so that a margin of the resilient material extends above the shot column.

It is sometimes desirable to utilize this upwardly extending margin of resilient material to complete the envelope surrounding the shot column.

In some cases the metallic shell is crimped to form an outer closure and in others it is desirable to utilize a top wad between the resilient material and the crimped shell.

The present invention has to do with that class of metallic shells wherein a top wad is included thus making it unnecessary to fully crimp the top of the metallic shell as will be more apparent hereinafter. Sometimes this top wad may be frangible and thus in need of protection.

In the mass production of shotshells utilizing the above noted liner or partition of resilient material it is highly important to design an envelope which may be readily closed. Furthermore, the steps practiced in assembling the elements of the shotshell must lend themselves to high-speed machinery.

Accordingly, it is a particular object of the present invention to provide a new and improved metallic shotshell.

Another object of the present invention is to provide a method for accomplishing a closure for a metallic shot shell.

Another object of the present invention is the provision of a shotshell having a novel top wad.

A still further object of the present invention is to provide a method of utilizing the top wad for accomplishing the closure of a plastic envelope around the shot column.

Another object of the present invention is to provide a new and improved top wad.

A method of practicing the present invention may include the steps of providing a metallic shotshell having a powder load and with conventional filler wads disposed above the powder, inserting a hollow cylinder of plastic material within the shell immediately above filler wads and concentrically disposed with respect to the longitudinal axis of the shell, loading the shell with the charge of shot so that a margin of the collar extends above the shot column, folding the margin of the paper collar inwardly so as to overlay the shot column, providing a top wad formed with a skirt portion, advancing the top wad into the shell so that the skirt portion tends to

2

separate the plastic collar from the shell and cams the margin of the collar inwardly so as to overlay the shot column and the step of bending the top of the shotshell inwardly so as to hold the top wad and thus the margin of the plastic collar in place.

5 A shotshell embodying certain features of the present invention may comprise a metallic shotshell having a primer assembly, a powder charge, an over-powder wad, conventional filler wad or wads disposed over the powder charge, a shot column positioned immediately above the filler wads, a plastic collar encircling the shot column and having a marginal portion overlaying said column so as to substantially enclose the top of the column, and a top wad positioned immediately above the enclosed column, said shotshell terminating in an inwardly extending arcuate crown.

10 A complete understanding of the method and the article of the present invention may be obtained from the following detailed description of a shotshell illustrating a specific embodiment thereof when read in conjunction with the appended drawings in which;

15 Fig. 1 is an elevation view, partially in section, of an aluminum shotshell embodying the present invention and showing a step in the method of accomplishing the shell closure;

20 Fig. 2 is a view of the top portion of Fig. 1 showing the initial contact of the top wad with the collar with upper part of the collar starting inwardly as a result of the camming action of the wad;

25 Fig. 3 is a view similar to Fig. 2 showing the top wad in the final position with the marginal portion of the collar completely folded upon the shot column;

30 Fig. 4 shows the step of forming the crown on the shell and the configuration of the shotshell after it has been curved inwardly to retain the top wad; and,

35 Fig. 5 is a sectional view of the frangible wad of the present invention showing to advantage the flange or skirt portion formed along the top and bottom edges thereof.

40 Referring now to the drawing and in particular to Fig. 1, there is shown an aluminum shell casing indicated generally by the reference numeral 10 having a side wall portion 11, a base 12, and a mouth 13. The shell is loaded with well-known elements such as a powder charge 15, over-powder wad 16, filler wads 17, and a shot column 18.

45 Disposed between the shot column and the interior of the shell side wall is a plastic collar 19. This collar may be formed of polyethylene, polyvinylchloride, or other suitable resilient plastic material and may be introduced in the form of a hollow cylindrical sleeve or a ribbon of material having a butted or lapped joint.

50 Frequently it is desirable to utilize a frangible top wad in a shotgun shell so that upon firing the shell, the shot column in striking the wad breaks the wad into a great number of small pieces thus providing substantially no interference to the advance of the shot toward the target. From time to time, prior to the present invention, the frangible wad has broken prematurely during handling by contact of the shot column therewith. In order to overcome this difficulty, it was proposed to extend the plastic collar 19 a sufficient distance above the shot column to provide a margin which may be utilized in a novel manner to cushion the frangible wad from the shot.

55 Accordingly, it was proposed that a frangible wad such as indicated generally by the reference numeral 21 be formed with a skirt portion 22 defining a knife edge which is utilized in cooperation with the flat sides 23 of the wad to cam an exposed margin 24 of the plastic collar inwardly to overlay the shot column. It is to be noted that the wad 21 need not necessarily be of the frangible

type for purposes of practicing the steps necessary to fold the margin 24 upon the shot column. Furthermore, it is to be noted that the wad is formed with a skirt on either side thereof. This is for convenience so that either side of the wad may be presented to the interior of the shell in assembling the elements of the shell.

Referring now to Fig. 2, the wad 21 is shown sufficiently advanced into the shell so that the skirt portion or knife edge 22 thereof has begun to separate the top portion 26 of the margin 24 turning it inwardly along the flat or cam side 23 of the wad. It is, of course, understood that the wad 21 may be advanced into the shell by any suitable means such as manually by utilizing an arbor press or by use of well-known automatic machinery.

Frequently it is desirable to slit the collar vertically (Fig. 1) at a plurality of spaced points, at least in the region of the margin 24 to facilitate turning the margin inwardly and to minimize or reduce buckling or wrinkling. The slits need not be disposed vertically but may assume an acute angle with respect to the longitudinal axis of the shell. It is entirely within the contemplation of the invention, however, to fold the margin inwardly without slitting.

Fig. 3 shows the wad after having been seated completely with the margin 24, fully cammed inwardly and overlaying the shot column. It is to be understood that the edges of folded margin 24 may be butted or lapped depending upon the distance the upright margin (Fig. 1) projects above the shot column.

Fig. 4 shows the finishing step wherein a forming tool 27 having an arcuate or hemispherical recess 28 formed therein is lowered into contact with the top of the shell. The tool is advanced against the shell with the result that the top of the shell is formed with an inwardly turned arcuate rim or crown 29. The tool is mounted for reciprocation by means not shown and the stroke may be adjusted to provide any desired degree of closure or arcuate configuration. The shell is generally finished with a central opening 31 as shown in Fig. 4. The primary function of the rim 29 is to protect the wad 21 and to retain it in position.

It is entirely within the purview of the present invention to manufacture the wad 21 from any suitable wad material.

It is to be further understood that the present invention need not be limited to metallic shotshells but may find use wherever it is desirable to provide a protective collar or hollow cylinder such as the cylinder 24 and to fold the marginal portions of the collar upon the shot column. A preferred material from which one may fabricate the collar 24 is polyethylene; but for purposes of practicing the present invention, it is not necessary to so limit the material for paper, rubber, or other resilient material is also satisfactory.

It is anticipated that the method of the present invention and the article thereof may be practiced and produced respectively in a variety of forms without departing from the spirit and the scope thereof.

What is claimed is:

1. In a shotshell having a conventional shot column, the method of enclosing the shot column in an envelope comprising the steps of providing an annular collar of resilient material, inserting the collar between the shot column and the interior of the shell, introducing a column of shot into the shell to a definite height so that a margin of the collar projects above the shot column, providing a top wad having a cam surface formed on one side thereof and terminating in a circular knife edge and advancing the wad into the shell so that the knife edge engages and separates the margin of the collar from the interior of the shell while the cam surface folds the margin over the top of the shot column.

2. In a shotshell having a conventional shot column, the method of enclosing the shot column in an envelope comprising the steps of providing an annular collar of resilient material, inserting the collar between the shot column and the interior of the shell, arranging said collar so that a margin thereof projects above the shot column, slitting the margin, providing a top wad having cam surface formed on at least one side thereof and terminating in a circular knife edge advancing the wad into the shell so that the knife edge engages and separates the slit margin of the collar from the interior of the shell and the cam surface folds the slit margin over the top of the shot column.

3. In a metallic shotshell having conventional shot column, the method of enclosing the shell comprising the steps of providing an annular collar of resilient material between the shot column and the interior of the shell, arranging said collar so that a margin thereof projects above the shot column, providing a top wad having a cam surface formed on one side thereof and terminating in a circular knife edge advancing the wad into the shell so that the knife edge engages and separates the margin of the collar from the interior of the shell and the cam surface folds the margin from the top of the shot column and curving the end of the shell adjacent the top wad inwardly to hold the wad in place.

4. In a metallic shotshell having conventional shot column, the method of enclosing the shell comprising the steps of providing an annular collar of resilient material between the shot column and the interior of the shell, arranging said collar so that a margin thereof projects above the shot column, providing a top wad having a cam surface formed on one side thereof and terminating in a circular knife edge advancing the wad into the shell so that the knife edge engages and separates the margin of the collar from the interior of the shell and the cam surface folds the margin from the top of the shot column and curving the end of the shell adjacent the top wad inwardly to hold the wad in place.
